LOOPER THREAD CONTROLLING MECHANISM FOR SEWING MACHINES

Edward Muecke, Linden, N. J., assignor to The Singer Manufacturing Company, Elizabeth, N. J., a corporation of New Jersey

Application April 30, 1943, Serial No. 485,148

8 Claims. (Cl. 112—242)

This invention relates to sewing machine thread-controllers and more particularly of the type to control the looper-thread of a chain-stitch sewing machine.

An object of the present invention is to provide a looper-thread control for a machine of this type whereby thread for the looper is pulled from the supply commensurate with the length of stitch.

With the above and other objects in view, as will hereinafter appear, the invention comprises the devices, combinations and arrangement of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a front sectional elevation of a sewing machine embodying my improvement. Fig. 2 is a top plan view of a portion of the sewing machine bed. Fig. 3 is an end elevation of the sewing machine head, partly in section. Fig. 4 is a detailed view of a portion of the thread-laying mechanism. Fig. 5 is a sectional elevation on line A—A of Fig. 2 of the looper thread take-up, nipper and pull-off mechanisms. Fig. 6 is a sectional elevation, on lines B—B of Fig. 2, of the feed actuating eccentric with its pull-off arm, thread-stripper and thread-guides cooperating therewith. Fig. 7 is a detail of the feed adjusting slide-block with pull-off finger. Fig. 8 is a detailed view, partly in section, of the looper-thread take-up and Fig. 9 is a detailed view, partly in section, of a portion of the mechanism for actuating the covering thread-laying device.

The invention is disclosed as embodied in a double-thread chain-stitch sewing machine having the usual bed 1 and bracket-arm 2 with overhanging head 3. Journaled in the bed 1 is the rotary main-shaft 4 with a belt-wheel 5 secured at its free end. The main-shaft 4 is also provided with spaced crank-disks 6 connected by a crank-pin 7 embraced by the lower end of a pitman 8 whose upper end is journaled upon a pin 9 extending from the crank-arm 10 fixed upon the upper rock-shaft 11 suitably journaled in the bracket-arm 2. The free end of the rock-shaft 11 is provided with a crank-arm 12 with a pin 13 having a link connection 14 with a pin 15 of a block 16 clamped upon the needle-bar 17 carrying at its lower end the spaced needles 18. The looper actuating mechanism embodied in this machine is shown and described in my

pending application, Serial No. 476,831, filed February 23, 1943.

It comprises an oscillating looper 19 supported by a carrier 20 secured at its lower end upon a shaft 21 journaled in the sewing machine bed, crosswise of the main-shaft. The looper receives its endwise or loop-seizing movements from an eccentric 22, fixed upon the main-shaft 4, and embraced by the strap-end of a short pitman 23 whose other end engages a ball stud 24 formed upon the end of a crank-arm 25 clamped upon the cross-shaft 21.

To impart sidewise movements to the looper, the carrier 20 is provided with an arcuately shaped clearance slot 26 entered by a slide-rod 27 provided with spaced collars 28 embracing the looper-carrier 20. The free end of the slide-rod 27 is provided with spaced ears 29 between which is mounted, on a pivot-pin 30, a lug 31 extending from a sleeve 32 embracing an eccentric 33 secured upon the main-shaft 4.

The sewing machine is further provided with a thread-laying mechanism comprising a spreader and thread-carrying implement for depositing, in advance of the needles, a covering thread upon the upper face of the work. In order to operate these parts the needle-bar actuating crank-arm 12 has pivotally mounted thereon a vertically disposed hollow sleeve 34 entered by a rod 35 extending upwardly from a collar 36 clamped upon a horizontally disposed slide-rod 37 entering a suitable bearing aperture in the head 3 of the bracket-arm 2. Depending from the collar 36 is a slide-block 38 embraced by the forked arm 39 secured upon a vertically disposed hollow bushing 40 suitably journaled in the head 3, embracing and forming a bearing for the presser-bar 41, carrying at its lower end the usual presser-foot 42 retained in work-engaging position by the flat spring 43. Clamped upon the lower free end of the hollow bushing 40 is a laterally extending arm 44 supporting the spreader 45. Also clamped upon the lower free end of the bushing 40 is a second arm 46 to the free end of which is pivotally secured a slide-block 47 entering a slotted rocker arm 48 pivotally mounted at 49 upon a bracket 50 depending from the head 3. Depending from arm 48 is a downwardly extending thread-carrying implement 51. During the stitching operation the spreader 46 and thread-carrying implement 51 deposit a covering thread in a sinuous path upon the upper face of the work and secure it thereon by stitches.

The feeding mechanism, of the usual four mo-

tion type, comprises the feed-dog 52 clamped upon the feed-bar 53 by the fastening screw 54. The feed-bar receives its rising and falling movements from the eccentric 55 mounted upon the shaft 4. The rear end of the feed-bar 53 is mounted upon a rocker 56 journaled upon the short shaft 57 supported by the sewing machine bed 1, in the rear of the main-shaft 4. Journaled upon the bearing stud 58 entering the feed-rocker 56 is one end of a pitman 59 whose other end embraces the adjustable feed-actuating ball eccentric 60 mounted upon the slide-block 61 disposed in the lateral transverse slide-way in the collar 62 fixed upon the main-shaft 4. The feed-cam or operating eccentric 60 is formed with an elongated clearance slot 63 embracing the main-shaft and the slide-block 61 has upon its rear face lugs 64 entering the annular grooves 65 in the head of an adjusting screw 66 fitted in a suitably threaded transverse aperture in the collar 62. Turning of the screw 66 serves to move its head within the counter-sink formed in the collar 62 and to thereby similarly shift the block 61 to vary the eccentricity of the cam or eccentric 60 carried thereby, resulting in a change in the stitch length.

Recessed in the block 61 and secured thereto by a fastening screw 67 is a looper thread pull-off or thread-engaging member 68 slotted at its free end to embrace a thread stripper-finger 69 secured upon the carrier-plate 70 by fastening screws 71. The carrier-plate 70 is secured upon a bracket 85 by fastening screws 86 and the bracket is secured by a screw 87 upon the upwardly extending pedestal 88 of the sewing machine bed 1. The stripper-finger 69 is provided with a thread-receiving slot 72 upwardly inclined at one end in the path of the pull-off finger 68. The upwardly inclined end of the thread-slot insures an early cast-off or disengagement of the thread from the pull-off member when the sewing machine main-shaft 4 is accidentally turned in the wrong direction (clockwise) thereby eliminating the danger of winding of the looper-thread around the feed-actuating eccentric. Secured by riveting or otherwise upon the under face of the carrier-plate 70, and projecting upwardly through suitable apertures 73, are two thread-guiding eyes 74 disposed upon opposite sides of the pull-off finger 68 and stripper 69.

Also mounted upon the carrier plate 70 is a looper thread-nipper comprising the opposed spring members 75 and 76 secured upon the carrier plate by a fastening screw 77. Projecting through a suitable aperture in the carrier plate 70 is a nipper actuating cam 78 secured upon the main-shaft 4.

The sewing machine is further provided with a looper thread take-up, such as is disclosed in the U. S. patent to A. B. Clayton, No. 2,095,212 of Oct. 5, 1937. It comprises a thread-cam 79 mounted upon the shaft 4 and projecting upwardly through a suitable slot in the carrier plate 70. Spaced above and secured to the carrier plate by a clamp-screw 80 is the thread-detainer 81 in the form of a U-shaped wire loop embracing the thread take-up cam 79. Adjustably secured by screws 82 upon the carrier-plate 70, and at opposite sides of the thread-cam 79, are the thread-guides 83 each of which is in the form of a hook having a forwardly opening thread-receiving throat leading to the bottom or reverse bend which guides the looper-thread, as more fully described in the Clayton patent above referred to.

To thread the looper, the end of the thread is first passed through a fixed tension device (not shown) at the rear of the bracket arm 2, thence through the eyelet 84 near the base of the arm, thence drawn forwardly beneath the sewing machine work-support (not shown) to the nearest thread-eye 74 on the carrier-plate 70, thence through the slot 72 in the stripper-finger 69, thence through the thread-eye 74 on the other side of the finger 69. From here the looper-thread is passed between the nipper springs 75 and 76 into the throat of the first thread-receiving hook 83 thence beneath the thread-detainer 81 into the throat of the second thread-receiving hook 83 and thence into the eye of the looper 19.

During the stitching operation of the sewing machine, the looper thread is controlled as follows: When the looper 19 moves forward in entering and seizing the needle-thread loops, the nipper springs 75, 76 are separated, with no drag on the thread. This permits free movement of the thread, as required by the looper, from a bight of thread previously drawn from the source of supply by the pull-off finger or thread-engaging member 68. During the backward movement of the looper, the nipper springs 75-76 are closed upon the thread, and the slack thread from the looper is taken up by the rotation of the take-up cam 79. During this time the pull-off finger 68 engages the thread and pulls off from the supply the required length of looper thread for incorporation in the next stitch.

In order to change the length of stitch the adjusting screw 66 is turned to shift the block 61 and vary the eccentricity of the cam 60. Such adjustment will also concomitantly change the effective path of movement of the thread pull-off finger 68 carried by the block 61 with respect to the stripper finger 69, increasing only by the necessary length the looper thread required for the succeeding stitch pulled off from the supply when the length of stitch is increased and vice versa.

It will be readily understood that the screw 66 constitutes a common element or interengaging connection between the block 61 and finger 68 for increasing the length of stitch and the length of looper-thread pulled off.

It will be observed that the sewing machine disclosed in the annexed drawings is provided with two rotary looper thread-controllers one disposed upon either side of the nipper, whereby, when the nipper springs 75 and 76 are closed upon the looper-thread, the controller 79 takes up the slack in the looper-thread during the retractive movement of the latter, while the other thread-controller 68 draws only sufficient thread from the supply for the succeeding stitch.

Having thus set forth the nature of the invention, what I claim herein is:

1. The combination with stitch-forming mechanism including an oscillating thread-carrying looper, of a nipper for the looper-thread, a stripper having a thread-receiving slot, thread-guides disposed upon either side of said stripper, and a rotary thread pull-off cooperating with said stripper and thread-guides for drawing looper-thread from the supply.

2. The combination with stitch-forming mechanism including an oscillating thread-carrying looper of a nipper for the looper-thread, a stripper having a thread-receiving slot inclined upwardly at one end, thread-guides disposed at either side of said stripper and a pull-off cooper-

ating with said stripper and thread-guides adapted for drawing thread from the supply when rotated in one direction and said stripper disengaging said thread from the pull-off when it is rotated in the opposite direction.

3. The combination with a sewing machine including a reciprocating needle, an oscillating thread carrying looper and a feeding mechanism, an adjustable feed-operating eccentric, of a looper thread pull-off device mounted upon said eccentric and including a rotary thread-engaging member governed in its path of movement by adjustment of said eccentric.

4. In a sewing machine, a rotary shaft, a collar on said shaft, an eccentric adjustably mounted on said collar, a thread-engaging member sustained by said collar and associated with said eccentric for adjustment with the latter, and stationary thread-guides cooperatively related to said thread-engaging member.

5. In a sewing machine, the combination with an adjustable feed-actuating eccentric including a collar provided with a transverse slideway, a block fitted in said slideway, an eccentric carried by said block, means for shifting the block and collar relatively and a thread-engaging member carried by said block.

6. The combination with a feeding mechanism of a sewing machine including a feed-dog, an eccentric for imparting work-advancing movement to said feed-dog, a looper thread nipper, spaced thread-guides for the looper-thread, a thread-stripper, an arm carried by said eccentric and cooperating with said thread-stripper and thread-

guides for pulling off looper-thread and means for adjusting the throw of said eccentric for concomitantly varying the amplitude of the work-advancing movements of the feed-dog and the length of looper-thread pulled from the supply.

5 7. The combination with a feeding mechanism of a sewing machine comprising a feed-dog, means for imparting to said feed-dog rising and falling movements, an eccentric for imparting 10 work-advancing movements to said feed-dog, a looper thread nipper, thread-guides for the looper-thread, a thread-stripper, a slide-block mounted in said eccentric, an arm carried by said slide-block and arranged to cooperate with said 15 thread-guides and stripper to pull off thread from the supply, and a common element for concomitantly varying the amplitude of the work-advancing movements of the feed-dog and the length of looper-thread pulled off from the 20 supply.

8. The combination with a feeding mechanism of a sewing machine including a feed-dog, an eccentric for imparting work-advancing movements to the feed-dog having a guide-way, a looper 25 thread nipper, thread-guides and a thread-stripper for the looper-thread, a block adapted for sliding movements in the guide-way of the eccentric, a thread pull-off arm for the looper thread carried by said block, and an adjusting screw 30 forming an interengaging connection between said block and eccentric for concomitantly varying the amplitude of movement of the feed-dog and the pull-off action of the arm.

EDWARD MUECKE.
